[57] CLAIM

The ornamental design for a combined holder for keys
and protective spray, as shown and described.

DESCRIPTION

FIG. 1 is a perspective view of a combined holder for
keys and protective spray showing my new design;
FIG. 2 is a front elevational view thereof;
FIG. 3 is a right side elevational view thereof;
FIG. 4 is a rear elevational view thereof;
FIG. 5 is a left side elevational view thereof;
FIG. 6 is a bottom plan view thereof;
FIG. 7 is a top plan view thereof;
FIG. 8 is a front elevational view of another embodiment
thereof wherein an expandable strap is included
on the left side;
FIG. 9 is a right side elevational view thereof;
FIG. 10 is a rear elevational view thereof, with the strap
in the expanded condition;
FIG. 11 is a left side elevational view thereof; and
FIG. 12 is a top plan view of FIG. 8.
